UNITED STATES PATENT OFFICE.

HARRY V. HUNT, OF SAN GABRIEL, CALIFORNIA, ASSIGNOR OF ONE-HALF TO CALIFORNIA TRUST COMPANY, A CORPORATION.

CHAPLET.

Application filed September 19, 1925. Serial No. 57,365.

This invention relates to means for carrying a core within a mold with which the same coacts, and it appertains more especially to such core-supports that are to be embedded in the metal that is to occupy the mold space.

The main object of the invention is to produce an article of the character described embodying a thinned-out part adapted to 10 fuse and combine with the hot metal flowing around the same.

A further object is the production of an article of the nature set forth which shall be so firmly held by the cast metal that its 15 ends can be riveted over in order to make tight joints and prevent leakage when subjected to fluid pressure and which chaplet may be drilled lengthwise without danger of coming out.

Another object is to provide an article of 20 the species mentioned possessing a standard middle portion as well as flanges and capable besides of having the ends engaging the latter cut to suit the depth of the space intermediate the core and the inner wall of 25 the mold.

A still further object is the provision in an article of the type specified of end flanges capable of being anchored either within or 30 outside of their perimetral edges to the opposite walls of the core and mold.

Still another object resides in producing an article of the class mentioned composed of a minimum number of simple parts, amenable 35 to low cost of manufacture, quickly assembled, besides readily placed in assigned position.

Other objects and advantages of the invention will become apparent as the specification 40 proceeds.

With the aforesaid objects in view, the invention consists of the novel combinations and arrangements of parts hereinafter described in their preferred embodiments, 45 pointed out in the subjoined claims, and illustrated on the annexed drawing, wherein like parts are designated by the same reference characters throughout the several views.

Succinctly outlined, the article under consideration includes in its organization a stud member provided intermediate its shouldered extremities with one or more circumferential enlargements on either side of a central portion. The latter may be made wider in

one direction than the other and pierced with as many openings therethrough as desired. By preference the outer limits of the enlargements and the widened portion are formed with thinned down edges or sharp 60 corners, while the material of the openings are correspondingly drawn point-like therefrom. Flange elements forced onto the shoulders of the member are capable of being anchored to the surfaces of the mold 65 and core wherewith they coact, by means passed either through or closely following the perimeters of these flanges.

The advantages of the invention as here outlined are best realized when all of its 70 features and instrumentalities are combined in the one and same structure, but, useful devices may be produced embodying less than the whole.

It will be obvious to those skilled in the 75 art to which the invention appertains, upon becoming conversant with the details thereof, that the same may be incorporated in several different constructions. The accompanying drawing, therefore, is submitted 80 merely as showing the preferred exemplification of the invention.

In the said drawing:

Fig. I is a top plan view of this invention, 85 provide core-support, with the upper flange thereof omitted;

Fig. II is a front view of the invention, both of its flanges being shown;

Fig. III is a horizontal section taken on the line III—III of Fig. II, looking thereon 90 according to the arrows, this view being shown as moved one-quarter of a turn around from that of Fig. I;

Fig. IV is a vertical section taken on the line IV—IV of Fig. II, looking from 95 the left toward the right in the direction pointed out by the thereto appertaining arrows, the position the parts occupy corresponding to that of Fig. III;

Fig. V is a transverse section of a mold 100 showing the application thereto of a series of these chaplets, before the core to be carried thereby is put in place; and

Fig. VI is a similar section to the preceding, but representing the core supported 105 in its assigned position.

Referring now to these several views for a detailed description of the invention thereby exemplified in one of its preferred embodiments, it will be observed that the 110

known parts of the core and mold wherewith the said chaplet is associated and coacts have been designated by letters of reference, instead of numerals as are used to denote the present improvement. This was done it will be understood, merely to intimate that the said parts are not treated or considered as pertaining exclusively to the latter, but are claimed herein only so far as they form therewith legitimate combinations of elements capable of yielding novel and useful results.

Of these reference letters A identifies the walls or sides of the lower part of a flask enclosing the sand in which the cast is made; B the mold board whereon the flask with the packed molding sand therein, rests; C face of mold wherefrom the pattern employed in making an impression in the sand has been withdrawn; and D core of sand held at a certain distance from the face of the mold to afford a space E whereinto the molten metal used to produce the casting, is poured. The parts hereinbefore mentioned constitute the drag or bottom section from which the cope or upper part of the flask has been removed. The casting to be made when both flasks are fastened together, exemplifying a six-sided hollow column.

In order to carry the core D and prevent the same from shifting at such times as the fluid metal is poured into the mold space E, a number of chaplets are interposed between the core and the inner surface C of the mold at various intervals according to its width and length. Structurally each of these chaplets is composed of three distinct parts, comprising a post or stud member and two similar flange elements, respectively designated by the reference numerals 11 and 13, 15, of which those last named are preferably alike and affixed at or adjoining the extremities of the member.

As shown, the stud 11 consists of a piece of cylindrically shaped rod, the middle section of which may be flattened as at 17, so as to produce sidewise extending comparatively sharp-cornered wings 19. The outer edges 21 of the latter, if desired, can be made relatively thin or drawn-out. As denoted at 23 there may be provided through the flattened portion or the wings, any number of openings, depending upon the size thereof. The present exemplification of the invention, shows one of these openings as being located centrally of the portion 17. By preference, the material of the member included within each opening, instead of being entirely cut-out therefrom, is merely pierced and then forced to one side of the flattened portion, in the manner of pointed prongs or tongues as indicated at 25.

Adjacent to its opposite terminals, the said member 11 is reduced in size or diameter so as to constitute necks 27 having in prox-

imity thereto right angularly arranged shoulders 29. Intermediate of the latter, the body of the stud has formed thereon, one or more circumferential enlargements or annular appendages 31, the faces of which may be acutely bevelled or drawn together so as to meet in a trenchant edge or rim 33, overhanging the sides of the member, preferably all around the same. In the embodiment of the invention illustrated, a pair of these enlargements are represented as disposed on either side of the flattened portion 17. Still it is conceivable that not only a single but also a multiplicity of peripheral protuberances may be formed with the surface of the said stud. The above named necks 27, if desired, can be recessed or cupped axially inward from their outer ends for a certain depth as at 34, in order to enable the same of being readily upset by blows or pressure applied thereon.

Taking over the said necks below their outer extremities and abutting against the shoulders 29, are the hereinbefore mentioned flange elements 13, 15. The latter are preferably of rectangular formation, and provided with apertures 35 located substantially in the middle thereof and having a tight or force fit engagement with the necks 27. At 37 it is denoted, that the said flanges may be formed with open outwardly facing notches in the perimeters of the same. Through these notches are adapted to be driven into the sides of the mold and the core, nails 39 or other headed pins capable of anchoring the combined flange elements and stud member constituting the chaplet, firmly in assigned position to resist the on-rushing sweep or force of the molten metal flowing around the same. Instead of pushing the nails through the notches, the former may be placed as depicted in Fig. I, in paired relation around the opposite corners of a flange, depending upon conditions and space available therefor.

Before the core D is placed in position within the mold C, the number of chaplets deemed necessary to support the former, are fastened to the side and bottom of the latter, by nails of suitable lengths stuck into the packed sand through or around those of the elements serving as basal flanges for the chaplets, in accordance with the arrangement depicted in Fig. V. Next the core D is put in place within the mold, resting upon the cap-flanges 13 of the chaplets, which flanges are then anchored to the adjoining faces of the core in a manner similar to the before mentioned basal flanges 15. After the companion or cope flask is set and locked in inverted position over the bottom or drag flask, the completed mold is ready to have the liquid metal poured into the space E thereof. The hot flowing metal in coming into contact with the thin and sharp corners

21, the tongues 25, and the edges 33, will cause these attenuated bonding means to fuse and combine with the molten metal flowing around the same, which metal subsequently cools and contracts about the chaplets, thereby becoming so firmly imbedded in the casting that they cannot come out or shake loose. The advantage of having the outer ends of the necks 27 project beyond the cap and basal flanges 13, 15, is that the former can be riveted over the latter. Thus if the chaplets are cast into metal walls exposed to fluid pressure and a leak should happen to develop 10 or appear around the necks, such leakage can readily be stopped by peening over the extremities 34 of the said necks. Both of the enlargements 19 and 31 will prevent the chaplets from being pushed through the 15 walls of the casting. Even if it should be required to drill a hole through the latter where a chaplet occurs or is located, the aforesaid enlargements will retain what remains of the chaplet around the bored 20 opening, in place. A foundry can conveniently keep on hand quantities of these stud members of certain maximum lengths having enlargements of this adopted type embodied therewith. And, as different jobs 25 come up, it is merely a matter of cutting off the ends of the studs and forming necks thereon for the reception of standard stock flanges. From the foregoing it will be perceived that a considerable saving of time 30 and simplified procedure is attained by the use of these chaplets.

While a certain preferred embodiment of this device has been shown and described, it will be understood that changes in the 40 form, arrangements, proportions, sizes and details thereof may be made, without departing from the scope of the invention as defined by the appended claims.

Having described my invention what I 45 desire to secure by Letters Patent and claim, is:—

1. In a chaplet having enlarged ends, a stud member incorporating lateral and end-wise anchorages disposed substantially parallel with and at an angle to the axis of said member, respectively, said anchorages being provided with bonding means at the edges thereof.
2. A chaplet provided with enlarged end flanges and with a one-piece spacing member

engaging the latter, said member having parts of substantially uniform cross-section intermediate its flanges and thin-edged bonding portions beyond said parts, said spacing member through said portions 60 affording positive anchorage in material cast thereabout.

3. In a chaplet having flanged ends, a post member spacing the same apart and embodying anchorage projections of unequal 65 thicknesses, said projections being substantially heavier at the juncture with the body of said member than at their edges.

4. In a chaplet having end flanges, an intermediary member holding the latter apart, 70 said member being provided with circumferential annular thin-edged projections spaced from each other and from said flanges, said projections extending beyond the body of the intermediary member and 75 overhanging the same.

5. In a chaplet including end flanges, a post member provided intermediate the latter with an aperture having sideways extending edges affording means for bonding 80 the same to the material cast therearound.

6. A chaplet having a post member, a plurality of end flanges engaged thereby, said member being provided with an aperture extending therethrough in a plane substantially parallel with the faces of said flanges 85 and at an angle to the axis of the post.

7. A chaplet having end flanges and a post member provided with a thin-edged annular enlargement projecting therefrom 90 intermediate of said flanges, said enlargement being independent of the latter and affording bonding means for said member in material cast thereabout.

8. A chaplet comprising end flanges and 95 an intermediary member, the latter being provided with flange engaging means and having an anchorage including a flattened portion between said means, said portion being disposed in the plane of the axis of 100 said member.

9. A chaplet comprising a stud member provided with a thin-edged enlargement, said member including necks with shoulders adjacent thereto, and flange elements lodged 105 against said shoulders having apertures taking over said necks, the edge of said elements being formed with notches adapted to receive anchoring means.
